UNITED STATES PATENT OFFICE

ALBERT A. WITZ, OF CHICAGO, ILLINOIS

DESIGN FOR A LAMP-STAND BRACKET

Application filed April 17, 1930. Serial No. 35,280. Term of patent 3½ years.

To all whom it may concern:

Be it known that I, ALBERT A. WITZ, a citizen of the United States, and a resident of Chicago, county of Cook, and State of Illinois, have invented a certain new, original, and ornamental Design for Lamp-Stand Bracket, of which the following is a specification, reference being had to the accompanying drawing, forming a part thereof.

In these drawings:

I claim:

The ornamental design for a lamp stand bracket, as shown.

ALBERT A. WITZ.
